UNITED STATES PATENT OFFICE.

WILLIAM A. RINGLER, OF PHILADELPHIA, PENNSYLVANIA, ASSIGNOR TO THE GLOBE-WERNICKE CO., A CORPORATION OF OHIO.

INDEX-ELEMENT CARRIER.

Application filed June 14, 1924. Serial No. 719,939.

This invention relates to visible index devices of the type in which a series of cards or elements bearing information are arranged in an overlapping relation, with portions of the several cards or elements exposed to view and carrying identifying or distinguishing characters thereon. More particularly the invention relates to the carriers or members which are arranged in a supporting frame, and which mount the cards or elements.

An object of the invention is to provide an improved index element carrier of this type which may be readily made, to a considerable extent, of relatively inexpensive materials by simple operations; with which the adjacent carriers will interlock with one another when assembled in a suitable supporting frame; with which any index card or element may be instantly removed from or attached to its carrier or be swung to expose either of its faces; and which will be durable and relatively inexpensive. Various other objects and advantages will be apparent from the following description of an embodiment of the invention and the novel features will be particularly pointed out in the appended claims.

In the accompanying drawing;

Fig. 1 is a plan of a number of the improved carriers, with a number of them carrying index cards, and all arranged as they are to be assembled in a supporting frame;

Fig. 2 is a plan of the reverse side of the same;

Fig. 3 is a plan of an individual carrier; and

Fig. 4 is a transverse sectional elevation through a number of the carriers assembled as in Fig. 1, the section being taken substantially along the line 4—4 of Fig. 1.

Referring first to Fig. 3 in which a single carrier is illustrated, this carrier comprises a strip 1 of suitable flat material, such as sheet-metal or heavy paper or cardboard. The strip is provided along one edge with a plurality of tongues 2 and 3, the tongues 2 being those nearest the ends of the strip and the tongue 3 being intermediate the others. The end tongues 2 are folded back upon the same face of the body of the strip and secured thereto in any suitable means, such as by eyelet rivets 4 which are passed

through the body of the strip and the folded-over tongues.

A wire 5 extends along the strip and into the pockets formed by the folded-over tongues between the eyelets and the folded edge, so as to be confined to the strip by the folded-over tongues. The ends of the wire 60 are preferably bent angularly as at 6, to hook over or cooperate with the eyelet rivets so that the wire cannot be displaced endwise from the pockets. The wire preferably passes over that face of the tongue 3 which is opposite from the face of the strip upon which the tongues 2 are folded.

A member 7, adapted to detachably support a card or index element, is hinged to the wire 5 above the tongue 3, so that the card and member 7 may be swung about the wire 5 as an axis or hinge for exposing either face of the card. The member 7 may be of any suitable construction for supporting the card, preferably detachably, and as illustrated comprises a sheet of metal having edge portions 8 and 9 turned over upon the same face of the strip so as to extend toward one another and form, with the body of the strip, a pair of opposing guide grooves, and with the portions 8 and 9 in different spaced planes. Tongues 10 upon the ends of the strip are rolled about the wire 5 so as to form hinge elements swinging thereon.

Each index card 11 is provided with a bent-over edge portion 12 which is inserted in the member 7 in the manner shown in Figs. 1 and 4, with the body of the card passing through the space between the edge flanges 8 and 9, and the edges of the turned-over edge portion 12 disposed in the opposing grooves so as to be anchored therein. Each card is inserted in its member 7 or removed therefrom by sliding the same edge-wise into the grooves, and to facilitate this insertion, one of the edge flanges 8 or 9 is made longer than the other at the ends so that the bent-over edge of the card may be readily inserted first in one groove, and then slid along the groove to carry the other edge of the bent-over portion into the other groove.

When the improved carriers are assembled side by side as shown in Figs. 1, 2 and 4, the tongues 3 will interlock or nest be-

neath the next adjacent carriers so that they will all be interlocked with one another as shown. With this interlocking, the carriers will not slide over one another in the grooves and will retain their regular spacing in the supporting frame. At the same time they may be separated as desired for the insertion of additional carriers. This type of carrier is exceptionally simple, and may be readily made by simple operations from relatively inexpensive sheet material.

It will be understood that various changes in the details and arrangements of parts, which have been herein described and illustrated for the purpose of explaining the nature of the invention, may be made by those skilled in the art within the principle and scope of the invention as expressed in the appended claims.

20 I claim:

1. A card carrier for index devices, comprising a strip of sheet material having tongues on a side edge folded back upon a face to form pockets, securing means passing through and attaching together the folded-over tongues and the body of the strip, a wire extending between the tongues and within the pockets, the ends of the wire being deflected somewhat around the securing means to prevent removal of the wire from the pockets, and an index card connected to the wire for swinging movement thereon to expose either face.

2. A card carrier for index devices, comprising a strip of sheet material having tongues on a side edge folded back upon a face to form pockets, securing means passing through and attaching together the folded-over tongues and the body of the strip, a wire extending between the tongues and within the pockets, the ends of the wire being deflected somewhat around the securing means to prevent removal of the wire from the pockets, and means carried by the wire for supporting an index card therefrom.

3. A card carrier for index devices, comprising a strip of sheet material having tongues on a side edge folded back upon a face to form pockets, securing means passing through and attaching together the folded-over tongues and the body of the strip, a wire extending between the tongues and within the pockets, the ends of the wire being deflected somewhat around the securing means to prevent removal of the wire from the pockets, and card-supporting means hinged to said wire.

4. A card carrier for index devices, comprising a strip of sheet material having tongues on a side edge folded back upon a face to form pockets, securing means passing through and attaching together the folded-over tongues and the body of the strip, a wire extending between the tongues and

within the pockets, the ends of the wire being deflected somewhat around the securing means to prevent removal of the wire from the pockets, and means carried by the wire for detachably supporting an index card 70 therefrom.

5. A card carrier for index devices, comprising a strip of sheet material having tongues on a side edge folded back upon a face to form pockets, securing means passing through and attaching together the folded-over tongues and the body of the strip, a wire extending between the tongues and within the pockets, the ends of the wire being deflected somewhat around the securing 75 means to prevent removal of the wire from the pockets, and an index card connected to the wire for swinging movement thereon to expose either face, said strip also having a tongue projecting from an edge to interlock 80 with an adjoining strip when the strips are arranged side by side in a securing frame.

6. A card carrier for index devices, comprising a strip of sheet material having spaced tongues along an edge, said tongues 90 being folded back upon the face of the strip, eyelet rivets passing through and securing together the tongues and body of the strip, and card-supporting means mounted between the strip and folded-back tongues. 95

7. A card carrier for index devices, comprising a strip of sheet material having spaced tongues along an edge, said tongues being folded back upon the face of the strip, eyelet rivets passing through and securing 100 together the tongues and body of the strip, and card-supporting means mounted between the strip and folded-back tongues and held against displacement on the strip by said eyelets.

8. A card carrier for index devices comprising a strip of sheet material having tongues on a side edge adjacent the ends and an intermediate tongue on the same edge, the end tongues being folded back beneath the strip, means for securing the folded-back tongues to the body of the strip, a member extending between the end tongues and secured between them and the body of the strip, the said member passing over the intermediate tongue, and an index card connected to the member, the intermediate tongue interlocking beneath the next adjacent strip when a plurality of the carriers are arranged side by side. 110

9. A card carrier for index devices comprising a strip of sheet material having tongues on a side edge adjacent the ends and an intermediate tongue on the same edge, the end tongues being folded back beneath the strip, means for securing the folded-back tongues to the body of the strip, a member extending between the end tongues and secured between them and the body of the strip, the said member passing over the inter- 115 120 125 130

mediate tongue, and a card support hinged to said member, the intermediate tongue interlocking beneath the next adjacent strip when a plurality of the carriers are arranged side by side.

10. A card carrier for index devices comprising a strip of sheet material having tongues on a side edge adjacent the ends, the tongues being folded back beneath the strip, members securing the folded tongues to the body of the strip, a wire extending along the strip and confined thereon by the folded tongues, the wire being bent in proximity to the securing members and held against displacement on the strip by the latter, and a card support secured to said wire.

11. A card carrier for index devices comprising a strip of sheet material having end portions folded over upon the body of the strip, members securing the folded portions to the body of the strip, and card-supporting means confined to a face of the strip by said folded portions and by said members.

12. A card carrier for index devices comprising a strip of sheet material having end portions folded over upon the body of the

strip, members securing the folded portions to the body of the strip, a wire confined to a face of the strip by said folded portions, and a support, to which an index card may be detachably secured, hinged to said wire.

13. A card carrier for index devices comprising a strip of sheet material having portions folded over upon and secured to the body of the strip, and card-supporting means extending over a face of the strip between its side edges, in a direction lengthwise of the strip, and confined to a face of the strip by said folded portions.

14. A card carrier for index devices comprising a strip of sheet material having portions folded over upon and secured to the body of the strip, and means for detachably supporting an index card, extending over a face of the strip between its side edges, in a direction lengthwise of the strip, and confined to a face of the strip by said folded portions.

In witness whereof, I hereunto subscribe my signature.

WILLIAM A. RINGLER.
